UNITED STATES PATENT OFFICE.

FRED HOVEY ALLEN, OF SOMERVILLE, MASSACHUSETTS.

GAS-BURNER.

SPECIFICATION forming part of Letters Patent No. 749,251, dated January 12, 1904.

Application filed November 28, 1902. Serial No. 133,107. (No model.)

To all whom it may concern:

Be it known that I, FRED HOVEY ALLEN, of Somerville, in the county of Middlesex and State of Massachusetts, have invented certain new and useful Improvements in Gas-Burners, of which the following is a specification.

This invention relates to improvements in gas-burners, and has for its object the production of a device for burning gas in any ordinary heating apparatus, which may be so adjusted that combustion may be made to take place at any desired point in the fire-box, and is provided with means by which air may be admitted in any required quantity, and is also provided with an obstruction to provide a perfect mixing of the air and gas before entering the pipes where the combustion occurs; and it consists in certain novel features of construction and arrangement of parts, which will be readily understood by the description of the drawings and to the claims to be hereinafter given.

Of the drawings, Figure 1 represents a sectional plan of a portion of an ordinary kitchen-stove with this invention applied thereto. Fig. 2 represents a cross-section of my improved burner, showing the burner-pipes at different angles. Fig. 3 represents a longitudinal section of a portion of the same, showing the attachment of the supply-pipe, the location of the mixing device, and the reservoir, with its cylinders surrounding it, to which the burner-pipes are attached. Fig. 4 represents an elevation of the reservoir. Fig. 5 represents a longitudinal cross-section of a portion of the supply-pipe, showing the nipple, perforations, and sleeve; and Fig. 6 represents a cross-section of the mixing device.

Similar characters designate like parts throughout the several figures of the drawings.

In the drawings, 1 represents the lining of an ordinary kitchen-stove inclosing the fire-box 2, in which is placed a burner 3, to which gas is supplied by the pipe 4, provided with a perforated end 5, which is connected by means of a flexible tube 6 to any desired gas-supply. Upon the supply-tube 4 is mounted a sleeve 7, capable of adjustment lengthwise thereon to cover or uncover the openings in the perforated end 5, as desired.

The burner 3 consists of a cylindrical reservoir 8, connected at one end by a nipple 9 to the supply-pipe 4, the nipple 9 being provided with a mixer 10, consisting of a pair of crossed wires which causes the gas and air being admitted to the reservoir to be thoroughly mixed upon entering the same. The nipple 9 screws into a reduced coupling 11, which is screwed into one end of the reservoir 8, the reduced end of said coupling being provided with an asbestos packing and binding-nuts 12 and 13.

Surrounding the reservoir 8 are a plurality of sleeves or short cylinders 14, each provided with a hollow boss into which is screwed a perforated pipe 15, extending radially from the said reservoir 8, the outer end of said perforated pipe 15 being provided with another perforated pipe extending parallel to the axis of said reservoir, the opposite end of which may be connected by a similar radial pipe 15 to the reservoir 8 or remain disconnected therefrom, as desired.

The reservoir 8 is provided with a series of slits 17, coacting with the inner ends of the pipes 15, so that communication between the interior of the reservoir and the pipe 15 may be had with said pipe or at various angles about the axis of said reservoir. The end of the reservoir 8 opposite to the gas-inlet is closed by a cap 18. Between the various sleeves or short cylinders 14 are collars 19, of asbestos or other non-combustible material, to form a packing to prevent leakage.

The perforated end 5 is provided with an inlet-nipple 20, secured to the flexible supply-pipe 6, through which the gas is admitted to the burner 3 through the pipe 4.

The narrow circumferential openings or slits 17 in the reservoir 8 are alternately on opposite sides of said reservoir. The short cylinders or sleeves 14 rotate on the reservoir 8, but when in use are limited to the length of the slits 17 in the reservoir, so that the pipe 15 may always communicate with said reservoir.

When the pipes 15 are moved beyond the slits 17, communication thereto is destroyed and such pipe will be placed out of action. When in use, the sleeve 7 is slid along the pipe 4 to cover or uncover the openings in the perforated end 5, as desired.

perforated end 5, crossing a greater or less number of perforations, thus modifying the amount of inlet, and thereby regulating the amount of air admitted to the supply-tube, 5 which it is essential should be adjusted by the user to the quality and pressure of the gas being used in order to obtain the best results.

When this device is attached for service, as shown in Fig. 1, the perforated burner-pipes 10 15 16 are capable of being turned from a horizontal position to any angle where combustion and heat are desired.

In Fig. 2 three positions are seen—a horizontal, a vertical, and an angle of forty-five 15 degrees. It is obvious that the burner-pipes may be moved into any position intermediate of these positions. By this ability to locate the burner-pipes at will around the central reservoir combustion may be uniform over 20 the entire surface of the fire-pot or confined to any part of it, thus in the latter case enabling the user of a cooking-stove having a water-back to force the heating of the water therein to the exclusion of the other parts or, 25 turning the burner-pipes toward the oven, more rapidly to heat it than otherwise it can be done. Upon the admission of the gas from the supply-pipe the quantity of air required to give the desired heat and flame from the 30 burner-pipes can be regulated by the sleeve on the pipe 4.

Having thus described my invention, I claim—

1. In a gas-burner, the combination of a 35 reservoir provided with a plurality of circumferential openings, a plurality of tubes radiating from said reservoir and each communicating with one of said openings, means whereby each of said radiating tubes may be 40 moved into various positions about the axis of said reservoir, and a plurality of perforated tubes parallel with the axis of said reservoir and each communicating with one of said radiating tubes.

45 2. In a gas-burner, the combination with a cylindrical reservoir having a plurality of narrow circumferential openings, of a plurality of short cylinders provided with burner-pipes and adapted to be moved into various 50 positions about said reservoir, and means for insuring communication between said reservoir and said pipes when in various positions.

55 3. In a gas-burner, the combination of a reservoir, a plurality of radiating burner-pipes adjustably mounted thereon and communicating therewith, a supply-pipe and an open-work or perforated partition between said supply-pipe and said reservoir to retard the flow and mix the gas and air as they enter 60 the reservoir.

65 4. In a gas-burner, the combination of a reservoir, a plurality of radiating burner-pipes adjustably mounted thereon and communicating therewith, a supply-pipe, a perforated section in said supply-pipe, and an

adjustable sleeve thereon for regulating the inlet of air through said perforations.

5. In a gas-burner, the combination of a reservoir, a plurality of radiating burner-pipes adjustably mounted thereon and communicating therewith, a supply-pipe, a perforated section in said supply-pipe, an adjustable sleeve thereon for regulating the inlet of air through said perforations, and a partition 70 75 provided with cross members between said supply-pipe and said reservoir to retard the flow of and mix the gas and air as they enter the reservoir.

6. In a gas-burner, the combination of a reservoir, a plurality of radiating burner-pipes adjustably mounted thereon and communicating therewith, a supply-pipe, a nipple 80 for the inflow of gas to said supply-pipe, and an open-work or perforated partition between 85 said supply-pipe and said reservoir to retard the flow of and mix the gas and air as they enter the reservoir.

7. In a gas-burner, the combination of a reservoir, a plurality of radiating burner-pipes adjustably mounted thereon and communicating therewith, a supply-pipe, a nipple 90 for the inflow of gas to said supply-pipe, a perforated section in said supply-pipe, and an adjustable sleeve thereon for regulating the inlet of air through said perforations. 95

8. In a gas-burner, the combination of a reservoir provided with a plurality of circumferential openings, a plurality of radiating burner-pipes adjustably mounted thereon and each communicating with one of said openings, a supply-pipe, and an open-work or perforated partition between said supply-pipe and said reservoir to retard the flow of and mix the gas and air as they enter the reservoir. 100

9. In a gas-burner, the combination of a reservoir provided with a plurality of circumferential openings, a plurality of radiating burner-pipes adjustably mounted thereon and each communicating with one of said openings, a supply-pipe, a perforated section in 105 said supply-pipe, and an adjustable sleeve thereon for regulating the inlet of air through said perforations. 110

10. In a gas-burner, the combination of a reservoir provided with a plurality of circumferential openings, a plurality of radiating burner-pipes adjustably mounted thereon and each communicating with one of said openings, a supply-pipe, a perforated section in 115 said supply-pipe, an adjustable sleeve thereon for regulating the inlet of air through said perforations, and an open-work or perforated partition between said supply-pipe and said reservoir to retard the flow of and mix the gas and air as they enter the reservoir. 120

11. In a gas-burner, the combination of a reservoir provided with a plurality of circumferential openings, a plurality of radiating burner-pipes adjustably mounted thereon and each communicating with one of said open- 125

ings, a supply-pipe, a nipple for the inflow of gas to said supply-pipe, and a partition of cross-wires between said supply-pipe and said reservoir to retard the flow of and mix the 5 gas and air as they enter the reservoir.

12. In a gas-burner, the combination of a reservoir provided with a plurality of circumferential openings, a plurality of radiating burner-pipes adjustably mounted thereon and 10 each communicating with one of said openings, a supply-pipe, a nipple for the inflow of gas to said supply-pipe, a perforated section in said supply-pipe, and an adjustable sleeve thereon for regulating the inlet of air 15 through said perforations.

13. In a gas-burner, the combination of a reservoir, a plurality of tubes radiating therefrom and communicating therewith, and a plurality of perforated tubes parallel with 20 said reservoir communicating with said radiating tubes at different distances from the center of said reservoir.

14. In a gas-burner, the combination of a cylindrical reservoir having narrow circumferential openings, a plurality of short cylinders mounted on said reservoir, each provided with a radial opening adapted to communicate with an opening in said reservoir, and a burner-pipe mounted in each of said radial 25 openings of said short cylinders.

15. In a gas-burner, the combination of a cylindrical reservoir having narrow circumferential openings, a plurality of short cylinders mounted on said reservoir, each provided 30

with a radial opening adapted to communicate 35 with an opening in said reservoir, a burner-pipe mounted in each of the radial openings of said short cylinders, a supply-pipe united to said reservoir, and an open-work or perforated partition at the union between said supply-pipe and reservoir to retard the flow of 40 and mix the gas and air as they enter said reservoir.

16. In a gas-burner, the combination of a cylindrical reservoir having narrow circumferential openings, a plurality of short cylinders mounted on said reservoir, each provided with a radial opening adapted to communicate 45 with an opening in said reservoir, and a plurality of perforated pipes parallel with said reservoir, each communicating with a radiating burner-pipe.

17. In a gas-burner, the combination of a cylindrical reservoir having narrow circumferential openings, a plurality of short cylinders mounted on said reservoir, each provided with a radial opening adapted to communicate 50 with an opening in said reservoir, and a plurality of perforated burner-pipes parallel with and at various distances from said reservoir and each communicating with radiating burner-pipes.

In testimony whereof I have affixed my signature in presence of two witnesses.

FRED HOVEY ALLEN.
